UNITED STATES PATENT OFFICE.

NORMAN APPENZELLER, OF MILWAUKEE, WISCONSIN, ASSIGNOR TO KIDWELL BOILER COMPANY, OF MILWAUKEE, WISCONSIN, A CORPORATION OF WISCONSIN.

BAFFLE FOR WATER-TUBE BOILERS.

Application filed February 2, 1927. Serial No. 165,278.

This invention relates to baffles for water-tube boilers of the series drum and tube type, and particularly to baffles which are located within and longitudinally of the rear bank of tubes in order to provide downward and upward passes for the products of combustion.

The object of my invention is to provide a metal baffling of simple, cheap, durable and efficient construction which can be readily associated with the interior of the rear tube bank without the use of bolts or similar fastening devices.

In the embodiment of my invention here-
15 in illustrated, the baffle comprises a series of relatively-thin cast iron plates having inter-engaging joint portions arranged to effect and maintain the close assembly of the plates throughout the baffling area, and having in
20 addition lateral fins which cooperate with the adjacent boiler tubes to maintain the plates in upright position, and this without impairing the heating surface of the tubes; all as will be hereinafter described and
25 claimed.

In the drawings—

Figure 1 is a vertical section through a portion of a rear bank of tubes and the upper steam-and-water drum of a boiler, showing my improved baffling in position.

Fig. 2 is a transverse section through a portion of the side walls of the boiler setting, showing a plurality of baffle plates.

Fig. 3 is a plan of the structure shown in
35 Fig. 2.

Fig. 4 is a vertical section, as on the line
4-4 of Fig. 2.

Fig. 5 is a perspective view of a pair of baffle plates, one superposed on the other.

Referring to the drawings, 10 designates one of the upper steam-and-water drums of a steam boiler of the series tube and drum type; and 11 designates the rear bank of approximately vertical tubes which connect the said drum with the underlying mud drum (not shown). This bank of tubes is medially divided throughout the width of the boiler by means of a novel baffling structure which depends from the upper drum and terminates short of the mud drum to afford downward and upward passes for the products of combustion amongst the tubes, as such products travel to the rearward breeching or smoke stack of the structure.

The baffling comprises rectangular rela-

tively thin plates 12 of cast iron which are built up row by row from a transverse member 13 supported in and between the side walls 14 of the setting. The upper edge of each plate 12 is formed with curved reinforcing flanges 15 which provide a longitudinal groove of approximately semi-circular cross-section materially greater in width than the thickness of the plates, as shown, and the faces of each plate adjacent its lower edge are provided with longitudinal fins 17. With the exception of the end plates at the right hand side of the structure (as illustrated) each of the plates is formed at one end with curved reinforcing flanges 16, which, similarly to the flanges 15, provide a groove of approximately semi-circular cross-section. The flanges 15 terminate short of that end of the plate remote from the flanges 16, and the fins 17 terminate short of the respective ends of the plate, so that a plurality of the plates can be assembled with interengaging joint portions, as illustrated.

The member 13 is preferably a thin cast-
18 iron plate having a basal reinforcing flange
17^a and also having along its upper edge
19 curved flanges 16^a which provide a longi-
20 tudinal groove throughout the length of the
21 plate. The member 13 constitutes, in effect,
22 a continuous basal baffle plate which in the
23 initial installation of the baffling is located
24 slightly lower than its correct position. The
25 first row of plates 12 are then supported on
26 the member 13 with the bottom edges of the
27 row seated in the grooved portion of such
28 member and with the abutting plane and
29 grooved ends of the adjacent plates in inter-
30 locking relation. The thin longitudinal
31 edges of the fins 17 bear against the adjacent
32 flanking tubes 11 and maintain the plates 12
33 in spaced parallel relation thereto, or sub-
34 stantially so, without impairing the heating
35 surface of the tubes. The end plates of the
36 row are preferably projected into the inner
37 side walls of the setting, as indicated at 18,
38 so as to compensate for slight variations in
39 the width of the furnace and to ensure close
40 joints between the walls and the contiguous
41 edges of the plates. The second row of
42 plates 12 are then erected on the first row,
43 with the bottom edges of the second row
44 seated in the grooves provided by the flanges
45 16 of the first row, and similarly the suc-
46 cessive rows of plates are built up and articu-
47 100
48 105
49 110

lated until the space between the basal supporting plate 13 and the drum 10 has been effectually closed by a metallic wall whereof the uppermost row of plates, by virtue of 5 their joint or knuckle connection with the proximate lower plates, are disposed at an angle to accommodate the curvature of the upper ends of the tubes. This done the basal plate 13, together with the superimposed 10 plates 12, is raised by jacks or other means, until the top row of baffle plates is in close contact with the drum 10, and the parts are thus temporarily held in close interlocking 15 relation until the brick side walls are completed, whereupon the jacks are removed. Thus an effective self-supported baffling structure, free from bolts or similar fastening devices, is erected within the rear tube bank of the boiler.

20 The grooves provided by the curved flanges 15 along the top of the uppermost row of baffle plates, afford a simple and efficient seat for an asbestos rope, as 19, which rope ensures a tight seal or gasket 25 joint between the said plates and the drum when the baffling is completed.

From the foregoing described construction embodying my invention it will be seen that 30 relatively thin cast-iron baffle plates of substantial dimensions are provided. The longitudinal flanges 16 co-operate with the longitudinal fins 17 to prevent the warping and buckling of the baffle plates not only while 35 they are being cast but also while they are subjected to the action of the boiler heat. These plates for a given area are of less 40 weight than the thick refractory tiles usually associated with the rear tube bank, and, therefore, they can be made and installed in 45 larger sizes and with less labor than is practicable with refractory tiles, thus decreasing the number of joints consequent upon the use of the latter. The novel cast iron baffling also overcomes the objections attendant the 50 use of feather edge tiling within the curved upper portions of the tubes, and, besides, such metal baffling is naturally less liable than refractory tiles to break at the joints.

It is of course to be understood that instead 55 of the particular supporting means herein shown and described for the baffle plates any other type of main support therefor may be employed; that if desired in any case the plates which are associated with the 60 bends of the tubes may be curved instead of straight, and that, in other respects, the disclosed construction may be modified without departure from the principle of my invention 65 and the scope of the appended claims.

60 I claim—

1. In a boiler of the series drum and tube type, the combination with the rearward bank of water tubes and the overlying drum to which they are connected, of integral cast 65 iron baffle plates assembled in successive

rows between adjacent tubes, the abutting longitudinal edges of the plates of the respective rows having articulated joints, said joints being formed by similar laterally extending flanges along the edges of the plates 70 of one row, there being a relatively wide arcuate groove between the flanges in which are seated the edges of the plates in adjacent rows, and means supporting the assembled plates and maintaining the uppermost 75 row thereof in close relation to the said drum.

2. In a boiler of the series drum and tube type, the combination with the rearward bank of water tubes and the overlying drum 80 to which they are connected, of integral cast iron baffle plates assembled in successive rows between adjacent tubes, the abutting longitudinal edges of the plates of the respective rows having articulated joints, said joints being formed by similar laterally extending flanges along the edges of the plates 85 of one row, there being a relatively wide arcuate groove between the flanges in which are seated the edges of the plates in adjacent rows and the bodies of said plates having spacing means in contact with the tubes, and means supporting the assembled plates 90 and maintaining the uppermost row thereof in close relation to the said drum. 95

3. In a boiler of the series drum and tube type, the combination with the rearward bank of water tubes, of integral cast iron baffle plates assembled in successive rows between adjacent tubes, the abutting edges of 100 the plates of the respective rows having interlocking joints, said joints being formed by similar laterally extending flanges along the edges of the plates of one row, there being a relatively wide arcuate groove between 105 the flanges in which are seated the edges of the plates in adjacent rows and said plates having longitudinal reinforcing and spacing fins bearing against the adjacent tubes, and means for supporting said plates in interlocking relation. 110

4. In a boiler of the series drum and tube type, the combination with the rearward bank of water tubes, of integral cast iron baffle plates assembled in successive rows between adjacent rows of tubes, the abutting edges of the plates of the respective rows having interlocking joints constituted by wide arcuate grooves in flange portions on the plates engaging the abutting edges of the 120 adjacent plates, said plates also having longitudinal reinforcing and spacing fins bearing against the adjacent tubes, and means for supporting said plates in assembled interlocking relation. 125

5. In a boiler of the series drum and tube type, the combination with the rearward bank of water tubes, of integral cast iron baffle plates assembled in successive rows between adjacent rows of tubes, the abutting 130

edges of the plates of the respective rows having interlocking joints constituted by wide arcuate grooves in flange portions on the plates engaging the abutting edges of the adjacent plates, said plates also having longitudinal reinforcing and spacing fins bearing against the adjacent tubes, and a continuous supporting plate having a grooved upper edge portion which receives the lower edges of the first row of baffle plates.

6. In a boiler of the series drum and tube type, the combination with the rearward bank of water tubes, of integral cast iron baffle plates assembled in successive rows between adjacent rows of tubes, each plate having a relatively wide arcuate groove in a flange portion along its upper edge and having lateral longitudinal fins spaced from 20 the lower edge of the plate, and means for supporting said plates in assembled interlocking relation.

7. In a boiler of the series drum and tube type, the combination with the upper drum, 25 and the rearward tube bank having curved converging end portions entering said drum, of baffling between adjacent rows of

tubes, said baffling including a row of angularly disposed plates arranged in close relation to the said drum and having a flexible 30 joint support along their lower edges, said plates having interlocking joint portions at their abutting ends formed of the thin edges of the plates of one row and relatively wide arcuate grooves in flanges along the edges 35 of the other row of plates.

8. A thin metallic baffle plate for boilers having similar laterally extending curved flanges along one edge, there being a relatively wide arcuate groove between the 40 flanges for the reception of the edge of another baffle plate.

9. A thin metallic baffle plate for boilers having similar laterally extending curved flanges along one of its longitudinal edges 45 and along one of its ends, there being a relatively wide arcuate groove between the flanges for the reception of the edge of another baffle plate.

Signed at Milwaukee, in the county of 50 Milwaukee and State of Wisconsin this 28th day of January, A. D. 1927.

NORMAN APPENZELLER.
